(57) **CLAIM**

The ornamental design for a reinforcement binding machine, as shown and described.

DESCRIPTION

FIG. 1 is a perspective view of front, top plan and left side of a reinforcement binding machine showing my new design;

FIG. 2 is a front view thereof;

FIG. 3 is a rear view thereof;

FIG. 4 is a top plan view thereof;

FIG. 5 is a bottom view thereof;

FIG. 6 is a right side view thereof;

FIG. 7 is a left side view thereof; and,

FIG. 8 is a perspective view of the reinforcement binding machine of FIG. 1 showing the condition of the wire bobbin case being opened. The broken line showing of environmental structure is for illustrative purposes only and forms no part of the claimed design.
